Filed Oct. 31, 1963, Ser. No. 77,228

Term of patent 14 years

(Cl. D16—2)

FIG. 1

FIG. 2

FIG. 1 is a rear perspective view of an automatic pipette unit showing our new design; with the electric cord member broken away to indicate indeterminate length;

FIG. 2 is a front perspective thereof; with the electric cord fragmentarily shown for convenience of illustration.

The dominant features of our design reside in the portions of the drawings shown in full lines. Stippling is employed for contrast in appearance.

We claim:

The ornamental design for an automatic pipette unit, substantially as shown and described.
